VERTICLE SCALE FOR DRAFTING MACHINES

Robert E. Pough, 414 Brookdale Drive,
Boise, Idaho 83702

Filed Feb. 16, 1970, Ser. No. 21,451

Term of patent 14 years

Int. Cl. D10—08

U.S. Cl. D52—6

FIG. 1

FIG. 2

FIG. 1 is a left front perspective view of the verticle scale for drafting machines embodying my new design;
FIG. 2 is a right rear perspective view as viewed from the bottom.

I claim:

The ornamental design for a verticle scale for drafting machines, substantially as shown.
